United States Patent Office

Des. 225,860
Patented Jan. 9, 1973

225,860

HOUSING FOR ELECTRONIC APPARATUS OR SIMILAR ARTICLE

Robert E. Kalvitis, Fairport, N.Y., assignor to Xerox
Corporation, Stamford, Conn.

Filed Dec. 14, 1970, Ser. No. 26,438

Term of patent 14 years

Int. Cl. D14—02

U.S. Cl. D26—5

FIG. 1

Des 225,860

PAGE 2

FIG. 2

FIG. 3

FIG. 4

FIG. 5

FIG. 6

FIG. 7

FIG. 1 is a left-hand front perspective view of a first embodiment of a housing for electronic apparatus, showing my new design.

FIG. 2 is a top plan view of said first embodiment.

FIG. 3 is a front elevational view of said first embodiment.

FIG. 4 is a left-hand side elevational view of said first embodiment.

FIG. 5 is a right-hand side elevational view of said first embodiment.

FIG. 6 is a rear elevational view of said first embodiment.

FIG. 7 is a left-hand front perspective view of a second embodiment of a housing for electronic apparatus, showing my new design; the other views thereof being similar

to those for said first embodiment with the exception of the number of push buttons on the front panel thereof.

I claim:

The ornamental design for a housing for electronic apparatus or similar article, as shown and described.
